UNITED STATES PATENT OFFICE.

JEAN N. BRENNER, OF KANSAS CITY, MISSOURI, ASSIGNOR TO READY-SET MARCELLER COMPANY, A CORPORATION.

HAIR-WAVING DEVICE.

Application filed July 28, 1925. Serial No. 46,552.

To all whom it may concern:

Be it known that I, JEAN N. BRENNER, a citizen of the United States, and a resident of Kansas City, in the county of Jackson and State of Missouri, have invented a certain new and useful Improvement in Hair-Waving Devices, of which the following is a specification.

My invention relates to improvements in hair waving devices.

One of the objects of my invention is to provide a hair waving device, which is simple, cheap to make, durable, not liable to get out of order, which is easily operated, and which is efficient in operation.

The novel features of my invention are hereinafter fully described and claimed.

In the accompanying drawing, which illustrates the preferred embodiment of my invention,

Fig. 1 is a reduced perspective view of my improved hair waving device, showing the lazy bars extended and the combs positioned to enter the hair.

Fig. 2 is an end elevation of the device, showing the lazy bars extended and the combs folded, reduced.

Fig. 3 is a full sized plan view, partly broken away, showing the combs and lazy bars in the folded positions.

Fig. 4 is an enlarged section on the line 4—4 of Fig. 1.

Fig. 5 is a cross section on the line 5—5 of Fig. 4.

Similar reference characters designate similar parts in the different views.

1 designates lazy bars comprising two sets, the adjoining bars of each set being pivoted to each other by suitable means, such as eyelets 2, so as to swing to and from a folded position.

3 designates curved combs disposed concentrically to each other, 4 an anchor comb, also curved, and having its convex side facing oppositely to the convex sides of the combs 3, and 5 pivot pins extending respectively through and pivoted in the eyelets 2, and each pin having at its inner end an eye 6. Each of the combs 3 and the anchor comb 4 has two holes adjacent to its outer longitudinal edge in which are respectively pivoted two adjacent eyes 6 on axes at right angles to the axes of the adjacent pins 5. By means of this pivotal arrangement, the combs 3 and 4 can swing laterally in the

eyes 6, and the lazy bars 1 can swing from the extended position, shown in Fig. 1 to the folded position shown in Fig. 3, alternate combs moving in opposite directions during such folding movement of the lazy bars.

In the operation of the invention, the combs are first disposed as shown in Fig. 1. The anchor comb 4 is then inserted into the hair at the top of the head, and the combs 3 are first inserted when in the position shown in Fig. 1.

The combs 3 and 4 are then swung laterally to the positions shown in Fig. 2, after which the combs are moved lengthwise to the positions shown in Fig. 3, which movement will effect the folding of the hair engaged into waves in which position the hair should be held for a few minutes to let it become set. Before waving the hair should be dampened to enable it to retain the waves. After the hair has been held for the time required, the combs and bars are swung to the position shown in Fig. 1 and released from the hair. The device may then be used to wave the remainder of the hair that has not been waved, in the manner already described.

I do not limit my invention to the structure shown and described, as modifications, within the scope of the appended claims, may be made without departing from the spirit of my invention.

What I claim is:

1. In a hair waving device, lazy bars, combs, and means connecting pivotally the lazy bars and the combs by which the lazy bars can swing so as to fold and the combs can swing on axes at angles to the axes of the lazy bars to and from positions in which they will overlap each other and lie flatwise under the lazy bars.

2. In a hair waving device, lazy bars, curved combs some of which are concentric with each other and one of which has its convex side facing oppositely to the convex sides of the other combs, and means pivotally connecting the lazy bars and the combs by which the lazy bars can swing so as to fold and the combs can swing on axes at angles to the axes of the lazy bars.

In testimony whereof I have signed my name to this specification.

JEAN N. BRENNER,
